UNITED STATES PATENT OFFICE

DAVID W. PYE, OF BROOKLYN, NEW YORK, ASSIGNOR TO TUCO PRODUCTS CORPORATION, OF NEW YORK, N. Y., A CORPORATION OF NEW YORK

COMPOSITE FLOORING

Application filed September 23, 1930. Serial No. 483,773.

This invention relates to a flooring having a metal base surmounted by a concrete layer. The flooring is designed particularly for use in vehicles such as railroad cars, busses, etc., where there is a material warping or other distortion of the metal base, and the object of the invention is to prevent such distortion from loosening or cracking the concrete surfacing. I accomplish the desired result by interposing an elastic layer between the metal base and the concrete surfacing, having such characteristics that it performs the double function of preventing transmission of the small movements to the warping, expansion, contraction etc. from the base to the concrete, and also acts as a bond to tie the concrete to the metal base.

More particularly, in laying my floor, I apply to the top surface of the metal base a coating of a slow-drying, ductile, viscous material, and I lay over this a layer of fibrous material, either a woven fabric or separate element, which will effectively adhere to the viscous material. Then, before the viscous coating has set, I apply the concrete layer.

The metal base may be of any suitable form, but I prefer to use a base of the type called "truss-plates". These comprise double sheets of metal spaced one above the other and having opposed inwardly deflected portions at various points suitably connected together to make a unitary, hollow structure.

For the viscous, ductile coating, I prefer to use an asphaltic preservative, or an asphaltic paint having little or no drier and an addition of linseed oil, such materials having the characteristic of remaining elastic for an indefinite time.

As the fibrous material, I may use burlap of a very large mesh or I may apply separated coco-fibres or other filamentous material, which may be readily embedded in the viscous coating and aid in forming an elastic layer.

To produce what is known as "flexible concrete" for the final layer, I may employ magnesium oxychloride cement and a wood filler, as saw dust or wood pulp, which may form over half of the concrete.

My invention is illustrated in the draw-

ing, wherein Fig. 1 is a plan of a metal base carrying an elastic coat surmounted by a layer of coarse burlap before the concrete is applied; Fig. 2 is a vertical section of the same; Figs. 3 and 4 are fragmentary vertical sections after the concrete has been applied and the floor thus finished, the position of these figures being illustrated by the correspondingly numbered lines on Fig. 1.

As shown in the drawing, 10 and 11 indicate the bottom and top plates of a metal base made of "truss plates". In various regions the bottom plate 10 is bowed upwardly at 12, the top plate correspondingly bowed downwardly at 13 and where these indentations touch, they are secured together, as by electric welding or a rivet 15.

To assist in locking the concrete in place, it has been customary to form projecting lips on the top plate 11 which overhang the ends of the depression 13. These lips are shown at 16 and are cut out from the portion 13 by making openings 17, the lips being then turned up into the general plane at the top, as illustrated for instance in Patent No. 1,302,822 to J. O. Madison.

In Figs. 2, 3 and 4, the heavy black line 20 indicates a layer of asphaltic preservative or other ductile coating which is applied to the entire top surface. 21 indicates the coarse burlap lying on this preservative and bound by it to the top of the metal plate. This sheet of burlap is preferably laid over the entire metal surface without reference to the depressions 13 across which the fabric extends in nearly a plane.

30 in Figs. 3 and 4 indicates the layer of flexible concrete. This is applied directly on top of the burlap and asphaltic preservative, and depresses the burlap more or less into the depressions of the metal plate as illustrated in Figs. 3 and 4 and passes through the meshes of the burlap, thus adhering both to the burlap and the ductile coating. At the depressions 13 the burlap becomes embedded in the lower portion of the concrete layer.

The concrete extends under the lips 16 so that it becomes effectively locked to the plate at the depressions, while some of the concrete passes also through the openings 17 and se-

cures a clinch on the underside of the top plate 11 as shown in Fig. 4. I have found however, that when the concrete is applied directly to the metal plate, it is likely to break loose, particularly from the flat surface between the depressions, and my intermediate layer of ductile coating and fibre, in addition to its elastic characteristic, is well adapted to form a bond for holding the concrete to the flat regions between the depressions, which constitute the major portion of the top surface of the metal base.

I have found that good results can be obtained by using coco-fibre in place of the burlap layer, the same being scattered comparatively evenly over the entire top of the metal plate. I may use various other filamentous materials scattered over the metal plate instead of the coco-fibre. In any case however, it is desirable to have the fibrous material in a substantially uniform layer.

I claim:

1. A composite flooring comprising a metal base, a coating of ductile material on the top surface of the base, a layer of coarse burlap on the ductile coating, and a layer of concrete on the burlap and ductile coating.

2. A composite flooring comprising a metal base, a layer of ductile material on the top surface of the base, a layer of coarse burlap on the ductile material, and a layer of flexible concrete on the ductile material and burlap.

3. In a floor, the combination of a base having flat top portions, a coating on top of said flat portion of material similar to asphalt in solution with little drier, a substantially uniform layer of fibrous material over the asphaltic layer described, and a layer of flexible concrete on the asphaltic and fibrous layer.

4. In a composite flooring of the character described, the combination of a metal base comprising bottom and top plates spaced apart and connected together by means of upward indentations on the bottom plate and downward indentations on the top plate and means joining such indentations, a layer of ductile material on the top surface of the metal base, and a layer of flexible concrete resting on the ductile material and bound by it to the metal base.

5. In a composite flooring of the character described, the combination of a metal base comprising bottom and top plates spaced apart and connected together by means of upward indentations on the bottom plate and downward indentations on the top plate, and means joining such indentations, a layer of ductile material on the top surface of the metal base, a substantially uniform layer of fibrous material over the ductile layer, and a layer of flexible concrete resting on the ductile and fibrous material and bound by it to the metal base.

6. A composite flooring comprising a metal base, a coating thereon comprising an asphaltic paint with little drier and with the addition of linseed oil, a substantially uniform layer of fibrous material in the coating and a layer of concrete or similar substance on the asphaltic coating and fibrous layer.

7. In a floor, the combination of a base having flat top portions, a coating of slow-drying ductile viscous material on top of said flat portions, a substantially uniform layer of fibrous material over the coating, and a layer of concrete united to the fibrous material.

In testimony whereof, I hereunto affix my signature.

DAVID W. PYE.
